BRASSIÈRE OR THE LIKE

George A. Kaufmann, Essex Fells, N. J.

Application October 30, 1934, Serial No. 750,618

2 Claims. (Cl. 2—42)

The present invention relates to breast supporting devices, such as brassières or combination undergarments having brassière-like upper portions, and comprises a novel device of this type which will conform to the figure of the wearer, will provide comfortable but adequate support for the breasts and which may be simply and economically made.

A feature of the invention is the provision of reinforcing portions in the lower portions of the breast pockets which portions are so constructed as to be stiff enough to provide the proper lift or support to the breasts over a substantial area while being soft enough to avoid undue or localized pressure.

For a better understanding of the invention reference may be had to the accompanying drawing of which—

Fig. 1 is a perspective view of a brassière embodying the invention, and

Fig. 2 is a similar view of the upper portion of a one-piece garment illustrating a modified form of the invention.

The brassière illustrated in Fig. 1 comprises the breast pockets 2 and 4, shoulder straps 6, and front and body sections 8 and 10 respectively. The pockets 2 and 4 in the embodiment of the invention illustrated in Fig. 1 are provided with lower reinforced portions 12 each of which is of relatively finely corded material with the cords 14 thereof extending vertically upward from the base of the pocket toward the upper apex of the corded portion. When the brassière is in use, each portion 12 applies a firm but gentle lifting pressure over a relatively large part of the under side of the breast and the entire brassière fits snugly and smoothly to the body of the wearer. The provision of the corded portions 12 with their vertically disposed, relatively fine cords, insures proper support without undue or localized pressure and gives a well formed appearance to the figure without undue accentuation of the breasts such as would occur with stiffer or less yielding supporting means.

Instead of forming the breast supporting portions as integral parts of the pockets of the brassière or garment, as in the embodiment of the invention illustrated in Fig. 1, such portions may be formed separately and then superimposed upon the lower portions of the breast pockets of a garment. For example, as shown in Fig. 2, portions 12a of finely corded material may be super-

imposed over the material 16 forming the lower portions of the breast pockets 2 and 4 of the brassière portion of a garment. The portions 12a are preferably stitched about their periphery or at least along the vertical edges thereof, to the material 16 and are positioned, as in Fig. 1, with the cords 14 thereof extending vertically of the garment.

Portions 12a may be triangular in shape, or as in the embodiment illustrated in Fig. 1, or may be more nearly square as illustrated in Fig. 2. Preferably, however, the vertical dimensions thereof should be greater at the center than at the sides to conform more nearly with the shape of the breast. In the particular embodiment of the invention illustrated in Fig. 2, the portions 12a are indicated as attached to the outer side of the garment. Obviously whether they are secured to the outer or inner side of the garment is purely a matter of appearance and is immaterial insofar as their function as breast supporting means is concerned.

The invention has now been described and two embodiments thereof have been illustrated. Obviously various changes might be made in the particular constructions illustrated without departing from the spirit of the invention.

The following is claimed:

1. In a brassière or the like, a pair of definitely formed breast receiving pockets, the lower portion of each pocket comprising below the nipple portion thereof a breast supporting vertically extending centrally disposed stiffening zone portion of relatively thick but uniformly flexible finely corded fabric material, each of said zone portions being of substantially the same width throughout a portion of its height, the portions of said pockets beside and above said zone portions being of a relatively thin material readily conforming to the contour of the breasts resulting from the firm support of the under sides thereof by said zone supporting portions, whereby the breasts are supported by the application of a firm but gently lifting pressure over restricted vertical zones underneath and without undue or localized pressure either underneath or on the sides thereof.

2. In a brassière of the character set forth in claim 1 wherein the breast supporting zones are formed of a finely corded fabric material with the cords extending vertically.

GEORGE A. KAUFMANN.
